US00D994354S

(12) United States Design Patent (10) Patent No.: US D994,354 S
(45) Date of Patent: * Aug. 8, 2023

(54) SMART MAKEUP MIRROR DEVICE

(71) Applicant: ICON AI Inc., Seoul (KR)

(72) Inventor: Min Young Shin, Seoul (KR)

() Term: 15 Years

(21) Appl. No.: 35/511,361

(22) Filed: Aug. 7, 2020

(80) Hague Agreement Data

Int. Filing Date: Aug. 7, 2020

Int. Reg. No.: DM/211703

Int. Reg. Date: Aug. 7, 2020

Int. Reg. Pub. Date: Feb. 12, 2021

(30) Foreign Application Priority Data

Feb. 21, 2020 (KR) 30-2020-0007840

(51) LOC (14) Cl. 06-07

(52) U.S. Cl.

USPC D6/309; D14/172
